Primary Examiner — Richard Kearney*Assistant Examiner* — Michael Hoffman(74) *Attorney, Agent, or Firm* — Acuity IP, LLC; Nathan S. Cassell(57) **CLAIM**

The ornamental design for a strap assembly for a facemask, as shown and described.

DESCRIPTION

FIG. 1 is a front perspective view of a strap assembly for a facemask showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The uneven-length broken lines depict environmental structure and form no part of the claimed design. The even-length broken lines represent stitching and form no part of the claimed design.
